UNITED STATES PATENT OFFICE.

HENRY AUCHU, OF EMPORIUM, PENNSYLVANIA.

DERRICK.

1,143,019.

Specification of Letters Patent. Patented June 15, 1915.

Original application filed June 29, 1914, Serial No. 847,896. Divided and this application filed March 9, 1915. Serial No. 13,181.

To all whom it may concern:

Be it known that I, HENRY AUCHU, a citizen of the United States, residing at Emporium, county of Cameron, and State of Pennsylvania, have invented certain new and useful Improvements in Derricks, of which the following is a specification.

This invention relates to derricks.

In drilling operations in the oil regions, 10 the common practice is to erect a wooden derrick. These derricks become permanent structures, soon go to pieces, and prove expensive if the drilling operation is unsuccessful as they are not adapted to be taken 15 apart and used at another location. The success of an oil well drilling operation can never be foretold and the cost of the derrick is lost if oil or gas is not struck.

My object is to provide a knock-down, 20 fire-proof, metal derrick having uprights and an improved cap frame combined in an improved manner, adapting the derrick for use in oil well drilling operations and, preferably, embodied in a derrick construction 25 which may be readily removed or taken down and moved from place to place if its use elsewhere is desired.

In carrying out the invention, I provide 30 standards or uprights, preferably composed of telescopic sections which can be drawn out or collapsed, and an improved top frame or cap combined with the hollow upper ends of the uprights in an improved manner, as fully set forth hereinafter.

35 The present application is a division of my application, Serial No. 847,896, filed June 29, 1914.

In the accompanying drawings: Figure 1 is a perspective of a complete derrick to 40 which my improvements are shown applied; Fig. 2, a detail sectional view showing the connection between the cap frame and the end of one of the uppermost standard sections; and Fig. 3, a perspective detail of the 45 cap frame when inverted.

The present improvements and combination of parts are applicable to any derrick having uprights provided with tubular or open upper ends, and while I do not limit

myself to the embodiment of the present 50 invention in any particular construction of derrick, it is shown as embodied in a derrick such as set forth in my co-pending application, Serial No. 847,896, filed June 29, 1914.

The derrick, as shown in Fig. 1, has a base 55 1, and standards or uprights secured thereto composed of tubular telescopic sections 2, 3, 4, 5, which fit freely and yet not too loosely within each other. Suitable means are employed for holding the sections in extended 60 or set-up arrangement. The uprights 2, 3, 4, 5 may be connected by braces 12, 19 and 21, and a ladder composed of sections 24 may be employed if desired, though constituting no part of the present invention. 65

My present invention embodies the cap frame 13 and its combination with the hollow upper ends of the uprights.

The cap frame 13 is composed of angle iron sides connected together and provided 70 at their corners with connectors 14 which have flanges 15 overlapping the outer faces of the angle iron section of the frame 13, and these members 14 are secured to the frame 13 by bolts 16. They have gudgeons 75 or lugs 17 which are received in the upper open ends of the tubular sections 4 and are detachably bolted thereto at 18.

When the derrick is taken down for removal to another point, the cap frame 13 is first removed by withdrawing bolts 18 80 and then the sections 5, 4, 3, 2 and braces 21, 12, 19 are taken down, section by section. The derrick is set up by first building the lowermost section, then the successively 85 higher sections are set up in their order, and finally, the cap frame 13 is secured by bolts 18.

Having thus described my invention, what I claim as new and desire to secure by Letters Patent, is:

In a knock-down derrick, the combination with uprights, the upper ones of which have hollow ends, of a cap frame consisting of independent angle iron side members and 95 angular corner connectors having flanges, said connectors fitting the walls of the angle iron side members and fastened to the ends

thereof and constituting a means for securing the side members together, said connectors having gudgeons received in the hollow ends aforesaid, and fastening means directly 5 and detachably connecting the gudgeons to said uprights.

In testimony whereof, I hereunto affix my signature in presence of two witnesses.

HENRY AUCHU.
